LIQUID CLEANSING AGENT CONCENTRATES

To prepare liquid concentrates of washing and cleansing agents having a high content of electrolytes on the basis of non-ionic, surface-active compounds, the simultaneous use of so-called hydrotropic substances or solubilizers is necessary. By their solubilizing capacity it is possible to divide homogeneously non-ionic tensides in salt-containing solutions and to impart to the cleansing agent concentrates a sufficient stability.

Whereas the sulfonates frequently used for this purpose as hydrotropic substances, as for example toluene sulfonate, xylene sulfonate and cumol sulfonate, generally comply with the requirements in the case of detergent concentrates on the basis of anion-active detergents, they are ineffective when using non-ionic, surface-active products. However, due to the smaller foaming capacity and the better wetting, emulsifying and cleansing properties, cleansing agents on the basis of non-ionic surface-active compounds are preferred in practice with regard to those basing on anion-active compounds. Therefore, there is a need for hydrotropic solubilizers, which are suitable for such cleansing agent concentrates on the basis of non-ionic tensides.

It is known that solutions containing electrolytes, of non-ionic surface compounds can be stabilized by the addition of determined phosphoric acid esters, such as for example phosphoric acid mono- or diesters of the alkylaryl-polyglycol ethers or of the alkyl-polyglycol ethers. However, the hydrotropic properties of these phosphoric acid esters are only slightly marked, and their effect is not sufficient to dissolve until clear or to disperse the amounts of non-ionic, surface-active compounds required for the preparation of cleansing agent concentrates, in the presence of high electrolyte concentrations. Thus, for example, in order to maintain in solution about 3 parts of a reaction product of 1 mol of nonyl phenol and 10 mols of ethylene oxide in 100 parts of an aqueous composition corresponding to a usual liquid cleansing concentrate, and containing about 7 % of weight of sodium tripolyphosphate, 2 % by weight of trisodium phosphate, 3 % by weight of sodium metasilicate and 1 % by weight of potassium hydroxide, there are required about 5 % by weight of a phosphoric acid mono- or diester of an alkylaryl-polyglycol ether or of a fatty alcohol polyglycol ether. Thus, the amounts of these phosphoric acid esters required for the stabilisation of the non-ionic detergent raw materials in solutions having high concentrations of electrolytes, are considerable and lead to a negative influence onto the properties, as for example the foaming capacity and the defoaming capacity, of the cleansing agents.

It has now been found that phosphinic acids or salts thereof of the general formula I

wherein R_1 is a straight-chained or branched alkyl- or alkenyl radical having 4 to 16 carbon atoms, preferably 6 to 10 and especially 8 carbon atoms, R_2 is alkyl having 1 to 4 carbon atoms, preferably the methyl radical,

and Y is hydrogen or the sodium or potassium ion, have excellent hydrotropic properties superior to the phosphoric acid esters mentioned, with regard to non-ionic, surface-active compounds, and are therefore, especially suitable for the preparation of liquid aqueous cleansing agent concentrates on the basis of non-ionic, surface-active compounds.

The invention further relates to liquid aqueous cleansing agent concentrates on the basis of non-ionic, surface-active compounds, characterized by a content of phosphinic acid derivatives of the general formula I

wherein R_1 , R_2 and Y have the above meanings.

Besides the non-ionic, surface-active products and the phosphinic acid derivatives of the formula I, the aqueous cleansing agent concentrates according to the invention generally contain products usually termed as skeleton substances, as they are described for example in the standard work Schwartz, Perry, Berch "Surface Active Agents and Detergents," volume II, (1958), pages 288 to 317. The proportion of these skeleton substances in the aqueous cleansing agent concentrates is generally up to 35 % by weight, especially 5 to 30 % by weight. Such skeleton substances are above all alkaliortho- and -polyphosphates, as for example sodium tripolyphosphate or potassium pyrophosphate, in amounts of up to about 20 % by weight, preferably 8 to 15 % by weight, or organic complexforming agents, as for example ethylene-diamine-tetra-acetate, trisodium citrate or the sodium of the nitrilo-triacetic acid, also in amounts of up to about 20 % by weight, especially up to about 12 % by weight, and alkali silicates, as for example sodium meta-silicate or sodium-di — or — trisilicate, in amounts of up to about 10 % by weight, especially up to about 8 % by weight.

The aqueous cleansing agent concentrates of the invention may furthermore contain alkali liquors in amounts of up to about 5 % by weight, preferably up to 3 % by weight, as well as, if required, further usual auxiliaries.

The content of the aqueous cleansing agent concentrates according to the invention of non-ionic detergent raw materials is generally at about 1 to 10 % by weight, preferably 2 to 5 % by weight, and the content thereof of the phosphinic acid derivatives of the formula I is at about 1 to 5 % by weight, preferably 1.5 to 3.0 % by weight. The content of water of the concentrates is mostly adjusted to about 65 — 85 % by weight and the pH-value is adjusted to the range of from 8 to 14.

Non-ionic surface-active products, as they may be contained in the liquid cleansing agent concentrates according to the invention, are described for example in the standard work Schwartz, Perry, Berch Surface Active Agents and Detergents, Volume II, (1958), pages 120 to 138. Preferred non-ionic detergent raw materials are for example:

- Alkylphenol oxethylates, especially those having 8 to 12 carbon atoms in the alkyl radical and a content of about 4 to 15 oxethylene units,
- straight-chained or branched, primary or secondary alkylpolyglycol ethers, especially those the

3

alkyl radicals of which comprise about 8 to 20 carbon atoms and which contain about 4 to 20 oxethylene units and, if desired, furthermore about 2 to 20 oxypropylene units in the molecule,

- c. Propylene-oxide ethylene oxide block polymers, especially the addition compounds of about 5 to 20 mols of ethylene oxide on 1 mol of propylene-glycol having a molecular weight of about 1800 to 3000,
- d. Alkylamine-oxyethylates, especially those having alkyl radicals of about 10 to 20 carbon atoms and about 4 to 15 oxethylene units in the molecule as well as
- e. Fatty acids oxethylates, especially those with alkyl radicals having about 8 to 20 carbon atoms and about 4 to 15 oxethylene units in the molecule.

The phosphinic acid derivatives of the formula I used in the invention as a constituent of the liquid cleansing agent concentrates have not only the excellent hydro-tropic properties but also, surprisingly, a good stability towards alkali liquors. They are normally soluble until clear in a concentration of, for example, 10 g/l in a 25 % sodium hydroxide solution at room temperature.

Especially interesting from the technical point of view is above all their capacity of imparting to non-ionic, surface-active products a sufficient stability in salt-containing solutions.

Compounds of the formula I preferably used according to the invention are those, in which the radical R_1 represents an alkyl radical containing 6 to 10 carbon atoms, especially the octyl radical, and wherein the

4

radical R_2 represents methyl. Also preferred are compounds of the formula I, the alkyl radicals of which contain, on the whole, at least 7 carbon atoms.

The following Table lists some Examples of liquid cleansing agent concentrates according to the invention and determines the stability of the liquid concentrates after standing for 24 hours at 20°C according to the following scale:

+ Clear stable solution

- Turbid solution inclining to the separation of the layers.

The Examples 1 to 15 correspond to the present invention, the Examples 16 to 45 are comparative products according to the state of the art. The composition of the cleansing agent concentrates in this Table is indicated in each case in percent.

The compositions indicated in the Examples may be used for example as liquid alkaline washing detergents for dish washers. Especially interesting is, however, their use as cleansers for industrial purposes in high-pressure and vapor stream cleansing apparatuses. Great value is set on the small foaming effect and a high cleansing and decreasing capacity. For this reason the slightly foaming non-ionic surface active compounds

25 slightly foaming, non-ionic surface-active compounds are preferred for this application; they meet the requirements when used together with the phosphates, silicates and alkalies and the phosphinic acids according to the invention. The compositions indicated in the Table as Examples may, of course, be varied to a large extent as to their constituents and the corresponding application.

Estimation of
the concentrates

What we claim is:

1. Liquid aqueous cleansing agent concentrates on the basis of non-ionic, surface-active compounds, having a content of compounds of the general formula

(I) 20

wherein R_1 is a straight-chained or branched alkyl or alkenyl radical having 4 to 16 carbon atoms, R_2 is alkyl having 1 to 4 carbon atoms and Y is hydrogen or the sodium or potassium ion wherein the content of compounds of the general formula is about 1 to 5% by weight.

2. Liquid aqueous cleansing agent concentrates as claimed in claim 1 wherein R_2 represents methyl.

3. Liquid cleansing agent concentrates as claimed in claim 1 which contain about 1 to 10 percent by weight of the usual auxiliaries,
